A technical drawing of a rectangular component. At the top, there is a horizontal slot with a width of 11.1 mm. The top edge is labeled '14'. On the left side, there is a vertical slot with a width of 1.1 mm, labeled '15'. On the right side, there is a vertical slot with a width of 1.1 mm, labeled '16'. At the bottom, there is a horizontal slot with a width of 1.1 mm, labeled '17'. The bottom edge is labeled '18'. The overall width of the component is 14 mm.

WIND WING

Albert P. Robinson, Seattle, Wash.

Application October 3, 1929, Serial No. 396,996

9 Claims. (Cl. 296—44)

My invention relates to windows and to wind wings or deflectors for use therewith to protect one sitting by an open window from a draught therethrough, and is particularly designed for use with automobile windows, more especially such windows as form a part of the usual front door construction.

The general object of my invention is to provide a wind deflector construction which is, in effect, built into the door frame, so that it is always available for use when required, and while my invention is not, in its broadest aspect, limited to a deflector which is always held in place ready for use, and contemplates the possibility of applying deflectors to automobile structures by merely providing means for supporting the separable wings, which are manually lifted from a storage space and put into place when the occasion demands, yet my invention is more particularly directed to constructions wherein the deflector is maintained in a storage chamber or space, ordinarily the same storage chamber as receives the ordinary drop window, and from which it may be lifted conveniently and without delay upon suitable guide means, from which latter it is non-detachable, into operative position.

Among the objects of my invention are to provide wind deflectors of this sort the several parts of which may be conveniently folded and dropped into such a storage chamber, and conveniently removed therefrom and placed in operative position; to provide means for retaining such deflectors in the inoperative or stored position, yet making them instantly and conveniently available when required; to provide means associated with the deflectors for maintaining them in operative position braced outwardly from the car, yet with folding braces to permit their movement through a slot into the storage chamber; to provide means for closing the slot admitting to the storage space, both when the deflectors are in operative and in inoperative position; to provide means for closing the gap between the upper and lower edges of the deflector and the window opening, so that drafts and dust and rain may not blow over and under the deflectors and thence into the car; and to provide means, in some forms, whereby the deflectors may be moved at will into and from the same slot as receives the usual window glass, the latter being displaced at such times to permit the deflector to move therethrough.

Other objects, and particularly such as refer more particularly to structural details, will be readily apparent from a study of the drawings at-

tached to this specification, of this specification, and the claims terminating the same.

My invention comprises the conception explained above in its broadest aspects, and in addition the various embodiments of the same, as shown in the accompanying drawings, described in this specification, and as will be more particularly defined by the claims which terminate the same.

In the accompanying drawings I have illustrated various embodiments of my invention, some suited to particular circumstances, and others to different circumstances.

Figure 1 is a general inside elevation of an automobile door, showing my invention in operative position, parts being broken away.

Figures 2 and 3 are, respectively, sections on the lines 2—2 and 3—3 of Figure 1.

Figure 4 is an elevation of a modified form of my invention, the window casing being shown in section.

Figure 5 is a section on the line 5—5 of Figure 4.

Figure 6 is a view similar to Figure 4 of a further modification, and Figures 7 and 8 are sections on the respective lines 7—7 and 8—8 of Figure 6.

Figure 9 is a view similar to Figure 4, showing a further modification, and Figure 10 is a section thereof, on the line 10—10 of Figure 9.

Figure 11 is a view similar to Figure 4 of another modification, and Figure 12 is a section therethrough on the line 12—12 of Figure 11.

Figure 13 is a detail section of the same construction, while Figure 14 is a section on the line 14—14 of Figure 12.

Figure 15 is a view similar to Figure 4 of another modification, and Figures 16 and 17 are sections on the lines 16—16 of Figure 15, illustrating this modification in two positions. Figure 18 is a transverse section on line 18—18 of Figure 17.

Figure 19 is a view similar to Figure 1 of another modification, while Figures 20 and 21 are sections on the respective lines 20—20 and 21—21 of Figure 19.

I will proceed to describe my invention in connection with the ordinary automobile door and window construction, since it is with such a construction that my device will have the greatest utility and widest application, but it must be kept in mind that it may be used, also, in conjunction with car windows and various other types of windows.

Wind deflectors are a great convenience upon

an automobile, allowing either front window to be lowered for better vision, air, and for signaling, without an intense draft upon the driver or persons upon the rear seat. They can become a serious menace to safety, however, if they become coated with snow, ice, dirt, or rain, and especially at night when the lights of approaching cars shine upon them, and by refraction through the rain drops or dirt upon them, effectually blind the driver. Yet there is no means, so far as I am aware, other than placing them edgewise to the car's forward movement, whereby they may be quickly moved from operative position, and this is a makeshift, since the already obscured glass is only placed where it will not be greatly obscured further, and is not removed from the field of vision of the driver. Such considerations have prevented the more general adoption of these deflectors, and by my invention I make it possible to overcome these disadvantages, and to have the deflectors ready for instant movement into or from position or use, without even the necessity of stopping the car, in all ways analogous to the manner in which the car windows are raised or lowered.

In Figures 1, 2, and 3 is illustrated the simplest embodiment of my invention, that in which it is adapted to the present type of window construction, without change in the latter, the wind vane or deflector being merely stored in an extra or separate pocket built into the inside of the car door. Thus, the door 1 is in effect a window casing, defining a window opening 10 in the upper part of the door, and a storage chamber 11 in the lower portion of the door. Communication is had into the storage chamber 11 through a slot 12' in the sill 12 of the window opening, and through this slot ordinarily moves the window glass 2. Customarily this is guided in slots 14 at each side of the window opening 10.

A wind deflector 3, usually of glass, is for protection ordinarily supported in a U-shaped frame 30. To permit of its storage within the chamber 11 of the ordinary automobile door now in use, I may provide an opening closed by a cover 15, and defined, if desired, by a partition 16 upon the inside of the door below the sill 12. This auxiliary storage chamber 17 is of a size to receive the deflector 3, without interference with the ordinary window 2. The wind wing may be provided with trunnions 31 and 32 at top and bottom, respectively, and sockets 33 within the storage chamber 17 receive these trunnions and hold the deflector in position within the pocket 17. Similar sockets 34 may be provided at the top and bottom of the window opening 10 to receive the trunnions and hold the deflector in operative position. One of these trunnions, as 31, may be slidable in a tube 30', forming part of the frame 30, and is backed by a spring 35. A button 36 protruding through a slot in the tube 30' (see Figure 1) enables the slideable trunnion 31 to be withdrawn from its socket 34 for the insertion or removal of the deflector.

To hold the deflector in operative position I employ some type of brace, but since it is also my object to close in the gap between the top and bottom of the deflector and the sill of the window frame, I employ, by preference, a stiff, substantially triangular vane 37, rigidly secured, as indicated at 38, to the top and bottom of the wing 3 or its frame 30, and provide suitable means, as indicated by the snap button 39, for securing the inner edges of these vanes to the window casing. 75 This prevents drafts, dirt, rain, etc., from being

blown over or under the edges of the deflector and into the car, and may be employed to advantage even with deflectors which are permanently attached.

The device thus described may be fitted into doors of the construction now in common use, without undue alterations therein, the deflector 3 being stored within the pocket 17 when not required, and being releasable therefrom, and capable of being brought into operative position with little or no difficulty, and in a short space of time. Likewise, it can be taken down and again stored away without loss of time or trouble.

In Figures 4 and 5 I have illustrated a construction which is similar to that already described, except that the deflector 3 is normally kept in the same storage chamber 11 as the ordinary window glass 2, being dropped thereinto through an opening in the sill 12 of the window casing, this, in the present instance, being separate from the slot 12', through which the window glass 2 is moved. This opening through which the deflector 3 is moved would be closed, ordinarily, at least when the deflector is in inoperative position, by a cover 18.

In this form it is necessary to provide some type of guide whereon or wherein the wind deflector or its frame 3 may be slidable. This is conveniently accomplished by providing a tube 4, lying within the storage chamber 11, and slotted to permit movement of the deflector and its frame 30 and tube 30' therealong, this tube receiving and guiding the sleeve 30' of the deflector, and serving as its lower journal or trunnion when the latter is in operative position. To hold the deflector in inoperative position, I may provide a dog 40, engaging within a suitable hole provided in the sleeve 30', and to release the same I may provide a trip finger 41 on the lever 42 which carries the dog 40, the dog and finger 41 being normally held in operative position by a spring 43, and a rod 44 projects through the sleeve 30', and bears against the trip finger 41, so that when the rod is depressed, the trip finger being moved outwardly will cause disengagement of the dog 40 from its hole in the sleeve 30', permitting the sleeve and the deflector 3 to rise slightly under the influence of a spring 45 in the bottom of the tube 4, at least to a point where it may be grasped and drawn upward into operative position. The upper socket 34, receiving the trunnion 31, is kept normally flush by means of a spring-pressed plate 34' (see Figure 4).

The form shown in Figures 6, 7, and 8 is substantially that of Figures 4 and 5, except that the dog 40 is omitted, and the cover 18', instead of being integral with the frame 30 and swinging therewith, is hingedly supported in the sill 12, being held in closed position by a suitable catch 18'', which retains the deflector 3 in the inoperative or stored position against the upward pressure of the spring 45, but upon release of the catch 18'' the cover 18' may swing aside and permit the deflector to move upward sufficiently to be grasped and moved then into operative position.

In Figures 9 and 10 the frame 30 of the deflector is guided for movement upon a rod 46, which extends from the top of the window opening 10 into the storage chamber 11, so that the frame 30 is guided thereon for vertical movement from operative position into fully inoperative position. To control this movement any suitable means may be provided, and I have shown a more or less conventional means, con- 75

sisting of the collar 47 secured to the downwardly projecting end of the sleeve 30' to slide said sleeve upon the rod 46, a link 47' pivotally supporting the collar 47 from an arm 48, the latter being swingable by a pinion and quadrant 49 operable by a handle 49', such as is employed for raising the ordinary drop window 2 in an automobile. Various other suitable means of raising the wind wing might be employed. It should be particularly noted that the rod 46 is received in a groove or recess in the front edge of the window opening, so that the front edge of the deflector 3 is substantially flush with or in contact with the window opening, and no draft can enter between them (see Fig. 10).

Figures 11, 12, 13, and 14 illustrate a construction which does not differ greatly from those previously described, but one which includes a joint intermediate the frame 30 and the rod 30'. This is preferably a piano hinge, and is indicated at 50. This positively closes the gap between the forward edge of the deflector 3 and the window opening. The rod 30' is in this instance guided in a slotted tube 46', and is engaged by a suitable dog 51 pivoted at 52 and operable by a press-button 5 to release the same, and to permit it to be projected upward, under the influence of the spring 45, as heretofore described. The catch 30', in this instance, comprises a small lever which projects through and engages under the edges of the slot in the sill 12 through which the deflector 3 is extruded. It will be noted, also, that the vane 31, generally triangular in shape, is of a size that it may close this slot to prevent the admission of dirt thereinto when the deflector is in operative position.

It may be desirable to utilize the same slot 12', through which the window glass 2 normally is extruded, to permit movement of the deflector 3, and an arrangement to this end is illustrated in Figures 15, 16, 17, and 18. Figure 16 illustrates the deflector in readiness to be moved through the slot 12', while Figure 17 illustrates it thus moved out and the window glass 2 ready to be raised or lowered. According to this arrangement, the window glass may be moved up or down independently of the deflector, and it is only necessary, in order to permit movement of the deflector through the slot 12', to lower the window glass and deflect it, or at least its forward edge, so that it is out of line with the slot 12'.

To accomplish this, the frame 20, which supports the window glass 2, is caused to rest, in its lowermost position, within a notch 21 of a slide 22, which can be engaged by the driver, and which is guided upon a transverse guide 23 within the storage chamber 11. A second notch 24 receives the deflector 3, and when in this position, as shown in Figure 18, the window glass 2 and the deflector 3 may be moved to bring either one into registry with the slot 12'. The construction otherwise is or may be the same as that already described, except that a second joint 53 may be provided in addition to the joint 50, as described in connection with Figures 11, 12, 13, and 14. This added joint gives greater freedom of movement to the deflector 3, with respect to its vertical slide 30'.

In Figures 19, 20, and 21 is illustrated a further arrangement permitting movement of the deflector through the same slot 12' as the window glass 2. The frame 20, at the forward edge at least, which carries the window glass 2, is provided with two or more pins 25 receivable in a track 26 within the window casing, each such track ter-

minating in its lower portion in a lateral extension 27 (see Figure 20), whereby, when the window glass is moved to its extreme lowermost position, it, or at least its forward edge, will be deflected laterally to move the window glass 2 bodily to one side. The deflector 3, at such times, is moved in the same direction as the window glass, under the influence of a spring 55, or like member, until it comes into registry with the slot 12', when it may be raised by any suitable means. 10 Since various means of raising the deflector have been heretofore described, it will not be necessary to describe any specific means, at this time, for raising the same, but it may be noted, especially in Figure 19, that I have shown a cam 15 slot 56, with which is engageable a suitable pin upon the guide 30', whereby the deflector may be caused to swing laterally to one side when it reaches its lowermost position, and again laterally from registry with the slot 12' when it has 20 reached its uppermost position, the ends of the slot 56 being curved for this purpose.

I have omitted details of the window glass raising devices, it being understood that any suitable means for raising the window glass 2 25 may be employed. Such means, also, may be employed to raise the deflector itself, and I consider these to be details of structure which are well within the capabilities of a mechanic who is installing such a device, or the designer 30 who is arranging it within a car door. I also consider that various modifications of detail may be made within the scope of my invention, which is concerned with the conception of which these various embodiments are illustra- 35

What I claim as my invention is:

1. A wind deflector for automobile windows comprising a deflecting plate adapted to be hinged along one side edge, and a vane hinged 40 along an end edge to swing against the face of the deflector plate and to project away therefrom, said vane being provided with means for securing to a door member when so projected.

2. A wind deflector for automobile windows 45 comprising a deflecting wing, means associated therewith for supporting the same in outwardly inclined position at the front edge of the window opening, and a vane shaped to substantially fill the angle between the wing and the sill, and supported upon the horizontal edge of the wing to move into the plane of the wing and away therefrom, and said vane having means for securing to the door when moved away from the wing. 55

3. In combination with a window casing having a slotted sill and a storage chamber therebeneath, a window glass slideable through the sill from said storage chamber into the window opening, a wind deflector movable upward from the 60 storage chamber into upright position in registry with the window opening, means supporting said deflector for swinging movement about an axis at its forward edge, from upright position into outwardly swung operative position, generally triangular vanes hinged to the deflector, to lie close thereto when in the storage chamber, and means to secure said vanes to the door to maintain the deflector in operative position, and to 70 close the space between the top and bottom edges of the deflector and the window opening when the deflector is in operative position.

4. In combination with an automobile door or the like having a window opening and a slotted 75

5 sill affording access to a storage chamber therebeneath, a wind deflector movable from an inoperative position, disposed within the storage chamber, through the sill slot into operative position adjacent to an edge of and inclined at an angle to the window opening, a closure disposed upon the upper edge of the deflector to close its slot when the deflector is in inoperative position, and a member mounted on the deflector to close its slot when the deflector is in operative position.

10 6. In combination with a window casing having a slotted sill and a storage chamber therebeneath, a wind deflector storable in and movable upward from said storage chamber through the sill into registry with the window opening, a cover plate for the sill slot through which the wind deflector is movable, a releasable catch to maintain said cover plate closed, and spring 15 means operable upon release of said catch to remove said cover plate and to project said deflector from its slot.

15 7. In combination with a window casing having a sill and a storage chamber therebeneath, a wind deflector storable in and movable upward from said storage chamber into registry with the window opening, and means including trunnion posts at top and bottom of the deflector, and sockets therefor at top and bottom of the window 20 opening, for supporting said deflector to permit its rear edge to swing, when the deflector is in registry with the window opening, outwardly thereof.

25 8. In combination with a structure having a window opening therein, a wind deflector movable between an operative position adjacent to one edge of and at an angle to such window opening, and an inoperative position outside the pro-

jection of such opening, and means for maintaining the deflector in operative position comprising stiff, generally triangular vanes mounted upon the top and bottom edges of the deflector for filling the angles at top and bottom between the deflector edges and the window opening, when the deflector is in operative position.

30 9. In combination with a window casing having a slotted sill and a storage chamber therebeneath, a wind deflector movable upward from the storage chamber through the sill into upright position in registry with the window opening, a stiff, generally triangular vane hingedly secured to the bottom edge of said deflector, to lie close thereto for passage through the slotted sill, and to swing 15 into a plane substantially normal to said deflector when the latter is moved into operative position, and means for securing said vane to the window casing to maintain the deflector in operative position, and the vane extended over said slot to 20 close the same.

35 10. In combination with a window casing having a slotted sill and a storage chamber therebeneath, a window glass slidable through the sill from said storage chamber into the window opening, 25 a hollow post, a wind deflector mounted thereon and movable therewith upward from the storage chamber through the sill into registry with the window opening, a deflector-raising spring engaging said post when the deflector is received 30 within the storage chamber, a catch holding said post and deflector down in opposition to the spring when received within the storage chamber, and a rod extending downward through said hollow post, and operable to release said catch 35 for projection of the deflector by said spring.

ALBERT P. ROBINSON.
